UNITED STATES PATENT OFFICE.

SAMUEL ALSOP, OF NEW YORK, N. Y.

IGNITION APPARATUS.

Application filed March 4, 1920. Serial No. 363,272.

My invention relates particularly to apparatus of the type of my U. S. Patent No. 1,289,595, issued December 31, 1918.

The main object of my present invention is to improve upon the construction of my former patent so as to increase the life and efficiency of the device and avoid accidents.

Details of the improvements will be found to reside in the particular construction and arrangement of the contacts, in the method of supporting the device, the method of holding the parts together, and the provision of ventilating means, of such a character as to prolong the life of the apparatus and avoid the possibility of explosion.

Figure 1 is a side view and partial longitudinal section of a device embodying the improvements of my invention shown attached to a support;

20 Fig. 2 is a front view of the apparatus; Fig. 3 is a transverse sectional view on the plane of the line 3—3 of Fig. 1, showing the method of holding the rotatable contact member in place;

25 Fig. 4 is a transverse sectional view on the plane of the line 4—4 of Fig. 1, showing the ventilating screen and guard;

30 Fig. 5 is a transverse sectional view on the plane of the line 5—5 of Fig. 1, showing the contacts in the normal or starting position;

35 Fig. 6 is a sectional view showing the rotatable contact member turned to an angle of about 60° from the position of Fig. 5 so as to produce a break in the ignition circuit;

40 Fig. 7 is a similar view, showing the rotary member turned 180° from the position of Fig. 5 so as to produce two breaks in the ignition circuit; and

Fig. 8 is a detail of a brush contact.

The main body or housing of the device 10 is preferably formed of insulating material, such as porcelain, and provided with a flange 11, which is secured to a support 12 by means of one or more screws such as 13, 18. This support will usually be the dash of the car, so that the device will be located under the hood. Preferably a face plate 14 is provided of sheet metal, which is cupped, as shown, so that its outer face is spaced away from the support 12. A yielding washer 15 is preferably interposed between the flange 11 and the dash.

55 The binding screws such as 16 and 17, to which the circuit wires are connected, pass

through the wall of the body 10 from the inside and are provided with clamping pieces such as 16'. Curved spring brush contacts 18 and 19 are secured to the binding screws 60 16 and 17. Preferably the base of each brush is reflexed, as at 20, and slotted, as at 20', to receive the binding screw 16. The head 21 of the binding screw is preferably angular or rectangular in outline, so that 65 it is held from rotation in a groove 22.

The rotary member or plug 23 is also preferably of insulating material and constructed so as to receive one or more contact members 24. These contact members are preferably of T-shape and, with their shanks 25, are loosely mounted in slots 26 in the plug 23. Each contact may conveniently be formed of two thicknesses of thin sheet metal stamped into the proper shape, as 75 shown.

The plug 23 is preferably secured in the body or housing 10 of the device, so that it will not accidentally come out in handling and so that its rotation is properly 80 limited. This may be effected by providing a groove 27 in the plug and a pin 28 in the housing which projects into this groove. This pin may be sealed in the housing by 85 sealing material 29, if desired.

To rotate the plug and vary the position of the contacts 24 I preferably provide a handle or thumb piece 30 with a shank or spindle 31, adapted to fit in a longitudinal recess 32 in the plug. This shank is preferably angular in cross section, or flat on one side, so that there can be no independence of rotation between the shank and the plug, although the handle and shank may be withdrawn, if desired. An indicator or 90 pointer 33 is carried by the handle 30 and adapted to travel over a scale or dial on the face plate 14, so as to indicate to the operator the angular position of the rotary contacts.

To prolong the life of the device it is desirable to provide ventilation so as to keep down the temperature and carry away the products resulting from the sparks produced at the gaps between the contacts. For this purpose I provide an air inlet 34 at the front end, and an air outlet 35 in the face plate in back of the dash, so that the air can draw through the device from front to rear when in operation. To insure an unobstructed 105 passage for the air I may provide a longitudinal groove either in the plug or housing, 110

such as 36, extending from front to rear, although, by making the plug 23 small enough in diameter with relation to the inside of the housing, sufficient air space may be provided. When boring the hole for the spindle or shank 31 in the dash 12 it should be made large enough to provide sufficient ventilation from the housing 10 through the dash into the space behind the face plate 14, so that 10 there will be an air passage to the outlet 35. Where the device is mounted beneath the hood I find it desirable to provide a fine mesh screen 37 to prevent the sparks in the housing from igniting the gasoline fumes 15 which are frequently present under the hood. This screen also keeps out dirt and foreign particles. It may be held in place by a yielding washer, such as 38.

The parts will be seen to be simple in construction, susceptible of quantity production and accurate assembly even by unskilled labor, and so arranged that there is nothing to get out of order. By rotating the plug and contacts 24 a break in the ignition circuit 25 may be created, so as to oppose a variable resistance to the passage of the current, and thus store up energy in the coils so as to produce a powerful ignition spark and insure firing of the motor even under conditions in 30 which the spark plugs would normally be inoperative. By turning the plug and contacts to the position shown in Fig. 7 when leaving the car and pulling out the operating handle 30 and shank 31, the ignition may be 35 "locked", that is, placed in condition so that the car cannot be started. To start the car it would then be necessary to insert the handle and rotate the plug back to the position of Fig. 5. As soon as the motor is started 40 the plug is rotated anti-clockwise until the desired condition is reached. The device being mounted on the dash or instrument board directly in front of the operator's seat, its handle is readily accessible for adjustment 45 and the dial is visible at all times, so that the operator may see the conditions existing.

I claim:

1. In an ignition apparatus, a housing having an interior groove, a spring contact brush 50 having a reflexed slotted foot, a binding screw extending outside of said housing and having a head for holding said foot in place in said groove, and a rotatable contact member co-operating with said brush within said 55 housing.

2. In an ignition apparatus, a housing, a stationary contact therein, a rotatable plug

in said housing having a transverse slot, and a thin sheet metal contact member loosely mounted in said slot for engaging said stationary contact. 60

3. In an ignition apparatus, a housing, a stationary contact in said housing, a rotatable plug within said housing having a transverse slot, and a thin sheet metal contact member mounted in said slot and having a curved head and an extended shank. 65

4. In an ignition apparatus, a housing, a spring brush contact mounted therein, a rotatable plug in said housing, and a T-shaped 70 contact carried by said plug and having its head engaged and held in place by said brush contact and said housing.

5. In an ignition apparatus, a housing having a groove, a brush contact having a 75 slotted foot secured in said groove, a binding post extending through said slot and having a head to hold said foot, a rotatable insulating plug in said housing, and a contact member carried by said plug and having a contact surface extending part-way around said plug.

6. In an ignition apparatus, a housing having interior grooves arranged opposite each other, brush contacts having feet 85 mounted in said grooves and having their free ends extending transversely part way around the inside of the housing, and a plug rotatable in said housing and supported by direct contact therewith and having contact 90 members with curved faces adapted to make and break contact with said brush contacts.

7. In an ignition apparatus, a housing, brush contacts secured therein and extending toward each other on one side of the inner surface of the housing, circuit terminals connected to said brush contacts within the housing, and a rotatable insulating plug within said housing having contact members with exposed faces extending less than half 100 way around said plug.

8. In an ignition apparatus, an insulating housing, interior contacts carried thereby, a rotatable plug in said housing, contacts carried by said plug, said plug having a 105 groove extending part-way around it, a pin carried by said housing and extending into said groove for holding said plug in said housing and limiting its rotative movement, and a thumb piece having a shank of non-circular cross section extending within said 110 plug to adjust said contacts.
